UNITED STATES PATENT OFFICE

CHARLES R. HULTGREN, OF CHICAGO, ILLINOIS, ASSIGNOR TO S. KARPEN & BROS., OF CHICAGO, ILLINOIS, A CORPORATION OF WEST VIRGINIA

REVERSIBLE SEAT OR CHAIR

Application filed July 15, 1929. Serial No. 378,473.

This invention relates particularly to a seat adapted for use in railway coaches, although the invention may be usefully employed elsewhere.

8 The primary object is to provide an improved seat which can be reversed in direction, and which, in the operation of reversing the seat, will be laterally shifted. A further object is to provide, in connection 10 with a suitable locking device, a clamping device which will secure the seat-structure upon its base, such clamping device being released when the locking device is released. An additional object is to provide for swinging 15 the back with relation to the seat to give clearance with relation to the back of another seat, in the operation of turning the seat.

The invention is illustrated in a preferred 20 embodiment in the accompanying drawings, in which—

Fig. 1 is a perspective view of a car-seat constructed in accordance with the invention; Fig. 2, is a broken detailed view illustrating 25 the manner in which the back is pivotally connected with the arms of the seat; Fig. 3, an enlarged sectional view taken as indicated at line 3 of Fig. 2; Fig. 4, an enlarged broken vertical longitudinal sectional 30 view, showing the seat-structure locked and clamped upon the base; Fig. 5, a broken view of similar character, showing the lock and clamping device released; Fig. 6, a sectional view taken as indicated at line 6 of 35 Fig. 5; Fig. 7, a broken sectional view taken as indicated at line 7 of Fig. 5; Fig. 8, a broken plan view showing the base and the mounting supported thereby which carries the chair-structure; Fig. 9 a broken 40 sectional view taken as indicated at line 9 of Fig. 5; and Fig. 10, a sectional view on a reduced scale showing a modification.

In the preferred construction shown in the drawings, A designates a base which may 45 be fixedly secured to a floor and which comprises standards A', connecting-bars A², and a mounting-plate A³ carried by the bars A²; B, a seat-structure having a frame B' equipped at its lower side with a mounting 50 B²; C, locking mechanism carried by the

base A; D, a clamping-lever co-acting with the locking mechanism; and E, a back-actuating link connected with the device D.

The frame, or supporting-base, A may be of any suitable construction. In the illustration given, the mounting-plate A³ is centrally supported upon the cross-bar A², being secured thereto by cap-screws 1. The plate A³ is shown provided centrally with a slot 2 which extends longitudinally with respect 60 to the base.

The seat-structure B is provided with arms 3 and a back 4. The back 4 is joined by pivotal connections 5 to the rear upper corner portions of the arms 3. As shown, the 65 back is equipped with plates 6 which are joined by pivots 7 to plates 8 connected with the arms.

The frame of the seat is equipped with blocks 9 which serve as stops. These blocks 70 are provided with rubber facings 9^a against which the lower margin of the back is pressed when the seat-structure is in the normal condition shown in Fig. 1.

The mounting B² with which the base-portion of the seat proper is equipped comprises, in the illustration given, arms 10 which have their outer ends secured to the seat-frame B'; a shiftable upper plate 11 connected by rivets 12 with the inner ends of 80 the arms 10; and a shiftable lower plate 13.

Secured to the lower plate 13 is a short post 14 which extends upwardly through the slot 2 and through a perforation 15 in the plate 11. The upper end of the post is furrowed, thus providing a slot 14^a which, as shown in Fig. 6, receives the web-portion of a bearing-member 16 which is disposed adjacent the upper surface of the plate 11.

The clamping-lever D extends through the slot 14^a and is connected with the post by means of a pivot 17. The short end of the lever D is indicated at 18. The other end of the lever has extending therethrough a threaded stud 19 which is secured to the lever 95 by nuts 20. Upon the upper end of the stud 19 is a lock-nut 21 having a reduced portion which affords a pivotal bearing for the inner end of the link E.

The upper plate 11 of the mounting B² 100

is equipped with a depending cam-stud 22 which works in an arcuate cam-slot 23 with which the fixed mounting-plate A³ is provided. The construction and arrangement are such that when the super-structure is turned about the post 14 as a center, the super-structure will be shifted through the medium of the cam-stud 22 and the cam-slot 23, it being understood that the post 14 will 10 reciprocate in the slot 2 of the fixed plate A³.

The locking device C comprises a rock-member 24 supported in bearings 25 with which one of the frame-members A² is equipped; a locking-pin 24^a actuated by the 15 rock-member 24 and a spring 24^b which serves to throw the locking-pin to the locking position. The member 24 is shown as comprising a longitudinally extending portions 24^c supported in the bearings 25, an arm 24^d 20 which actuates the bolt 24^a, an arm 24^e, a depending portion 24^f, and a pedal-portion 24^g. The pedal-portion 24^g is shown as projecting slightly beyond the end of the base-frame A, but it should not project beyond the 25 end of the super-structure.

The link E, as stated, has its inner end pivotally connected with the lock-nut 21 on the stud 19. Its outer end is connected by a pivot 26 to the lower portion of the frame 30 of the back 4. The stud 19 is disposed over the locking-bolt 24^a when the seat is in the position shown in Fig. 4. The locking-bolt extends through a slot 27 in the lower plate 13, through a perforation 28 in the fixed plate A³ and through a perforation 29 in the upper plate 11. Normally, the bolt 24^a presses the outer end of the clamping-lever D upwardly, and thus lifts the post 14 and plate 13. In this manner, the fixed plate A³ 40 is normally clamped between the upper and lower shiftable plates 11 and 13. The purpose is to prevent possible rocking or chattering of the super-structure on the base A. In the illustration given, the shiftable plates 45 11 and 13 are provided at adjacent sides with raised marginal portions 30 which bear against the intermediate fixed plate A³. As shown in Fig. 7, the plate 13 has cut-away portions, indicated at 31, adapted to slidingly 50 engage the adjacent edge-surfaces of the bars A². The plate 13 may be raised slightly between the bars A² and may shift in the direction of the length of the bars A².

The operation may be stated briefly: 55 When it is desired to reverse the seat-structure, the operator depresses the treadle 24^g and withdraws the bolt 24^a from engagement with the upper shiftable mounting-plate 11. When the bolt 24^a is withdrawn, 60 the clamping pressure is relaxed through the medium of the lever D; and when the seat-structure is forcibly turned about the pivot 14, the mounting-plate 11 is caused to revolve and also is given a movement of translation, 65 due to the action of the cam connections 22

and 23. The lower plate 13 partakes of the movement of translation, but does not revolve. The post 14 is fixed to the lower plate 13 and thus the post and the clamping-lever D do not revolve. As the seat-structure is turned to effect reversal, the link E turns about the pivot 21. This causes the lower portion of the back to swing outwardly and thus throws the upper end of the back forwardly. In this manner, clearance is given to enable the seat to turn, notwithstanding the fact that the back of an adjacent seat may be close to the back of the seat being revolved. Ordinarily, the backs of the seats recline somewhat; and in the action of revolving the seat, the upper end of the back is tilted forwardly sufficiently to give the necessary clearance. It will be understood, also, that inasmuch as the seat-structure shifts laterally on the base-structure, the seat-structure is withdrawn sufficiently from the side-wall of the car to give the necessary clearance. 70 75 80 85

As will be understood from Figs. 4 and 8, the upper plate 11 is provided with a plurality of locking perforations 29. Two of these perforations are diametrically opposed, and one or the other serves to receive the bolt 24^a at the end of a rotation of 180°. 90

It will be noted that the cam-stud 22 and cam-slot 23 permit a turning movement of the seat-structure through an angle of 180° only. Thus, the seat-structure may be swung in one direction to face it forwardly, and then may be swung in the reverse direction to face it reversely. 95 100

If desired, the feature of swinging the back to give clearance may be omitted. In other words, the back may be rigidly mounted on the seat-frame. In such case, if desired, the seat-structure may be turned through an angle of 90° so that the seat will face the window. In this case, the odd perforation 29 shown in Fig. 8 will serve to receive the locking-plunger 24^a. 105 110

In the modification shown in Fig. 10, the construction corresponds mainly with the construction previously described and the corresponding parts are given the same reference characters. In the modification, however, the locking device, designated 'C', is shown as consisting of a bolt 32 equipped with a transverse stud 33 which is actuated by means of a cam-slot 34 provided in a longitudinally shiftable bar 35 which is suspended on hangers 36. The bar 35 is provided with slots 35^a which engage pins with which the hangers 36 are equipped. A spring 37 normally holds the bar 35 in the locking position. A treadle 38 (shown broken) is connected by a link 39 to one end of the bar 35. By this means, the bar may be shifted against force of the spring 37 to effect release of the locking device. When this occurs, the clamping-lever D is also released. 115 120 125

The foregoing detailed description has been 130

given for clearness of understanding only, and no unnecessary limitations should be understood therefrom, but the appended claims should be construed as broadly as permissible, 5 in view of the prior art.

What I regard as new, and desire to secure by Letters Patent, is:

1. In combination: a base; a chair-structure shiftably and pivotally mounted on said 10 base and equipped with a seat and a back tiltably related to said seat; connections between said chair-structure and said base serving to effect shifting of the chair-structure in the operation of turning the chair-structure; and means for actuating said back with relation to said seat in the operation of turning said chair-structure on said base.

2. A device as specified in claim 1 in which the means for actuating the back comprises 20 a link connected with the back and eccentrically connected with the base.

3. In combination: a base; a chair-structure having a central post depending therefrom shiftably connected with said base, said 25 chair-structure being equipped with a pivotally mounted back; means for effecting shifting of the chair-structure on the base when the chair-structure is turned with respect to the base; an arm extending from 30 said post; and a link connecting said arm and the lower portion of said back.

4. A structure as specified in claim 3, in which the arm mentioned comprises a clamping-lever pivotally connected with the post.

5. In combination: a base; a chair-structure shiftably and pivotally mounted on said 35 base; means connecting said chair-structure and said base serving to cause shifting of the chair-structure with relation to the base 40 when the chair-structure is turned on the base; clamping means normally clamping the chair-structure on the base; a lever for actuating said clamping means; a locking device normally engaging said lever and locking 45 the chair-structure against turning; and means for simultaneously effecting release of the clamping device and locking device.

6. In combination: a base equipped with 50 a mounting plate; a chair-structure equipped with a pair of mounting plates embracing said first-mentioned plate; means for effecting shifting of said second-mentioned plates in the operation of turning the chair-structure on the base; means effective to grip said 55 second-mentioned plates against said mounting plate; and a locking device adapted to lock said plates and actuate the gripping means.

60 7. In combination: a base; a surmounting chair-structure; connections between said chair-structure and base for effecting shifting of the chair-structure when it is turned with relation to the base; clamping means 65 connecting said base and chair-structure; and

a spring-actuated locking device serving to actuate said clamping means.

8. In combination: a base equipped with a horizontally disposed mounting-plate, having a guide-slot therein; a chair-structure having its base-portion equipped with an upper clamping plate and a lower clamping plate embracing said first-mentioned plate; a post depending from said upper clamping plate through said slot and connected with said lower clamping plate; a clamping lever pivotally connected with the upper portion of said post; and a locking device equipped with a plunger adapted to work through perforations in said plates and co-act with said clamping lever.

9. A structure as specified in claim 8, in which the locking device comprises a spring-held treadle adapted to actuate said bolt.

10. In combination: a base equipped with a horizontally disposed mounting-plate provided with a straight slot and with a curved cam-slot; upper and lower clamping plates embracing said first-mentioned plate and shiftable with relation thereto, the lower clamping-plate being non-rotatable; a post connecting said upper and lower clamping-plates and slidable in said straight slot; a cam-stud depending from said upper clamping-plate and moving in said cam-slot; a clamping-lever connected with said post and adapted to cause said clamping-plates to grip the intervening plate; a spring-actuated locking device having a bolt engaging said plates and normally holding the clamping-lever in clamping position; and a chair-structure rigidly mounted on the upper clamping-plate.

11. In combination: a base equipped with a horizontal mounting-plate provided with a straight slot; a pair of plates embracing said first-mentioned plate; a post connecting said pair of plates and movable in said straight slot; cam-connections between said plates; a locking device associated with said plates; and a chair-structure rigidly mounted upon the upper plate.

12. A structure as specified in claim 11, in which the post is vertically movable with relation to the first-mentioned plate and one of the other plates, and equipped with a clamping-lever which co-acts with said locking device.

13. In combination: a base equipped with a longitudinal guide and a mounting-plate carried thereby; upper and lower clamping plates embracing said mounting-plate, the lower plate being movable in said guide; a post connecting said clamping-plates and movable in a slot with which said mounting-plate is provided, said post being movable through the upper clamping-plate; a clamping-lever connected with the upper end of said post; cam-connections between said plates for effecting shifting of the plates; a

chair-structure fixedly mounted on the upper clamping-plate; and a spring-held treadle connected with the base and equipped with a locking-bolt extending through perforations in said plates, and normally holding said clamping-lever in the clamping position.

14. A structure as specified in claim 13, in which the chair-structure is equipped with a pivotally mounted back, which is connected 10 by a link to said clamping-lever.

15. In combination: a base; a chair-structure shiftably and pivotally mounted on said base; means connecting said chair-structure and said base serving to cause shifting of the chair-structure with relation to the base when the chair-structure is swung on the base; and releasable lever actuated clamping means normally clamping said chair-structure against said base. 70
